UNITED STATES PATENT OFFICE.

ELIZA LUMMIS, OF NEW YORK, N. Y.

DESIGN FOR A MEDAL OR SIMILAR ARTICLE.

SPECIFICATION forming part of Design No. 30,752, dated May 16, 1899.

Application filed April 7, 1899. Serial No. 712,182. Term of patent 14 years.

To all whom it may concern:

Be it known that I, ELIZA LUMMIS, of New York, in the county of New York and State of New York, have invented and produced a new and original Design for Medals; and I do hereby declare that the following is a full, clear, and exact description thereof, reference being had to the accompanying drawings, and to the letters of reference marked thereon, which 10 form a part of this specification.

My design consists of a medal having a certain ornamentation on the face thereof, and it is fully shown in the accompanying drawings.

Figure 1 represents a front view of the 15 medal. Fig. 2 is a section of the medal, taken on line 2 2 in Fig. 1.

The leading feature of my design consists of an oval border surrounding the following objects in bas relief; the representation of a 20 sable robe A, having its two upper corners gathered and separately confined by a cord, so that the folds of the robe outside of the cord at each corner shall form a fleur-de-lis, and the ends of the cord on either side have tassels

appended to them between the robe and the 25 oval border. The middle of the sable robe is occupied by the representation of an "osten- 30 sorium," so-called, and on each side of the osten- 35 sorium are represented the forms of two angels in the act of adoration, the four forms occupying the four corners of the robe. The upper border of the robe is carried up in the middle in a curve from each gathered corner and surmounted by a crown. The space between the crown and upper border of the oval 35 is occupied by a scroll, the shape of which conforms to the shape of the oval border above it.

Having thus described my design, I claim and desire to secure by Letters Patent—

The design for a medal or similar article 40 herein shown and described.

In witness whereof I have hereunto set my hand.

ELIZA LUMMIS.
